ELECTRICAL SOCKET

Gordon B. Pollock, South Laguna, Calif.

Application February 4, 1946, Serial No. 645,447

1 Claim. (Cl. 173—328)

This invention relates to electrical sockets for the reception of electric lamps, connectors, and the like, and pertains more particularly to an electrical socket adapted for the reception of so-called "photoflash" lamps such as are employed in photography.

One of the particular objects of the invention is to provide an electrical socket construction adapted to secure an enforced electrical contact with an electric bulb or the like, so that an optimum electrical circuit is established upon insertion of the bulb within the socket.

A further object of the invention is to provide an abrading type of electrical socket or the like, adapted to mechanically and electrically engage the electrical contact portions of the bulb or other element to be received within the socket, and to retain such bulb or the like in such socket.

A further object of the invention is to provide an abrading type of electrical socket for reception of an electric bulb or the like, wherein at least one of the abrading elements adapted to make electrical contact is adapted to function as a resiliently biased retaining means to maintain such bulb or the like within the socket in electrically operative position.

A further object of the invention is to provide an abrading type of electrical socket for reception of an electric bulb or the like and having one electrical contact of the spring-biased type adapted to resist the insertion of a bulb, together with another electrical contact member also of a spring-biased type adapted to mechanically and electrically engage the bulb during the insertion thereof and retain the same within such socket against the biasing action of the first-named electrical contact member, such last-named electrical contact member being releasable to permit ejection of the bulb from such socket under the influence of said first-named electrical contact member.

In many electrical uses, where it is desired to make an electrical connection of the type where a plug-like element is inserted within a tubular or recessed element as the electrical contact is made, it is essential or at least desirable to cause the electrical engagement of the contact members to present a desired minimum electrical resistance. In particular, in so-called "flash-bulb" photography, the character of the electrical contact obtained upon insertion of a bulb greatly influences the instant of ignition of the bulb in the production of the required "flash." Ordinarily, it is the practice of skilled photographers to employ a rather strong source of energy for

the ignition of the bulb, so as to overcome slight differences in the electrical resistance of the socket, to thereby reduce the percentage error in the ignition time of the bulb. It will be appreciated that when shutter speeds on the order of $1/200$ second are employed in a camera, an unwanted delay of $1/50$ second in the ignition of the flash bulb might well result in loss of the photographic exposure, without knowledge thereof on the part of the photographer.

As a further expedient to reduce the possibility of a delayed ignition of the bulb, many photographers make the practice of abrading the bulb tip (usually of soft-solder-like metal) upon some material such as sand-paper, to remove any accumulated dirt or film of oxidized metal from the contact. It is not appreciated, however, that the base-portion of the bulb (at which one side of the electrical circuit is established) may also be of varied electrical resistance characteristics, and little or no effort is made to compensate or correct for this condition.

I have determined that when a positive electrical contact at the bulb base is established, as by causing the contact elements within the bulb-socket to exert a positive abrading action at the position of the electrical contacts, whereby a consistent minimum electrical resistance is obtained, energy sources such as electrical batteries may be made of considerably less power (with a consequent saving in weight) and very consistent results obtained over a relatively long period. For example, while it is common practice among commercial or "news" photographers to use three fresh medium size batteries in series (4.5 volts) to flash a General Electric #5 flashbulb, I have found that it is entirely practicable to flash this type of bulb with two "pen-light" batteries in series, and to continue to flash such bulbs over a materially longer period than has heretofore been considered practicable without de-synchronization of the shutter and flash; the length of time one set of batteries appears to be useful, when a socket of the type considered by this application is employed, appears more to be limited by the available "shelf-life" of the batteries, than by the number of flashes which have been effected.

The socket construction of my invention is adapted particularly for reception of and contact with an electric lamp or element of the bayonet base type, in which one of the contact areas of the element is provided by the smooth side wall of the base, which is generally cylindrical in shape and extends parallel to the direction of

relative movement thereof in inserting the element in the socket, the other contact area of the element being provided at the inwardly disposed end of the base, generally centrally thereof.

According to the present invention, I provide a socket construction in which the central contact is of an abrading type, such as a pin member or conical point which will penetrate the soft-metal tip on the bulb, and arrange a second abrading contact element within the socket in position to engage and abrade the side-wall portion of the bulb-base as it is inserted within the socket, thus providing positive abrading contacts at the two electrical positions required for the completion of the electrical circuit to the flashbulb. According to the preferred construction, I provide the second contact element in the relation of a retaining means for the bulb, whereby the bulb is firmly engaged by such contact element and caused to persist within the socket.

In its broader aspects, the invention is concerned with a socket construction adapted to receive an electrical element having at least one contact area at which an electrical connection is to be made, wherein an abrading and retaining type of contact member is provided to engage such contact area and make both a mechanical and electrical engagement. Further, the construction may include spring means adapted to be stressed upon placement of such element within the socket, to produce a biasing action tending to eject the element from the socket, which action is opposed by the abrading-retaining contact member. The construction may comprise, for simple "flash-bulb" use, merely two abrading contact members adapted to respectively engage the spaced contact areas on the bulb-base, to establish a minimum electrical resistance upon insertion of the bulb within the socket.

Other objects and features of this invention will be brought out in the ensuing description of certain illustrative forms of construction, or will be apparent from such description with reference to the accompanying drawings, in which:

Fig. 1 is a partly fragmentary vertical section of a so-called "flash-gun," provided with a socket construction according to this invention;

Fig. 2 is a rear elevation of the form shown in Fig. 1, as taken on line 2-2 therein;

Fig. 3 is a vertical section of a modified form of socket construction, showing a flash bulb retained therein;

Fig. 4 is a plan view of the form shown in Fig. 3, as taken on line 4-4 therein;

Figs. 5 through 7 are transverse sections through a camera body provided with a socket construction according to this invention, taken in three different planes, Figs. 5 and 7 being taken on lines 5-5 and 7-7 respectively in Fig. 6, and Fig. 6 being taken on line 6-6 in Fig. 7, and

Fig. 8 is a vertical fragmentary section of a camera case provided with a form of abrading socket construction according to this invention, in which conventional retaining means are provided to retain a bulb or-like element within the socket.

Referring to Figs. 1 and 2 of the drawings, a flash-gun reflector is indicated at 1, having a central mounting opening 2 into which a socket 3 extends, the reflector 1 being carried against the rearward surface of a forward flange 4 on the socket 3. The bulb-retaining and contact means 5 may comprise an apertured body portion 6 of metal disposed about the socket 3, an attachment portion 7 riveted or otherwise secured to a bat-

tery case or handle portion 8, and an elongated portion 9 punched out to define an electrically-conductive and resilient bulb-retaining and contact finger 10. The finger 10 is adapted to extend within a longitudinal slot 11 in the socket with the free end thereof adapted to engage the base of a bulb inserted within the socket. Means are provided for releasing the finger 10 from engagement with the bulb base, such as a release lever 12 provided at one end with pivot arms 13 to retain the lever 12 with respect to the portion 9, suitable retaining recesses 14 being provided in the portion 9 to receive the arms 13. The socket 3, reflector 1 and bulb-retaining and contact means 5 may be interconnected in operating position through the agency of a snap ring 15 disposed in a suitable annular recess in the socket 3 and bearing against the rearward surface of the body portion 6. The lever 12 is provided with an opening 12a through which the finger 10 projects, the edge portion of the opening 12a serving as a cam to lift the finger out of the full-line position to the dot-dash position 10a upon depression of the lever to the position 12b.

The socket 3 is provided with a central bore 16, at the rearward end of which I provide a central contact member 17 provided with a forwardly directed abrading contact point 18. An ejector spring 19 is provided to bias the contact 17 forwardly, as against a shoulder 21 on the contact 17, and a rearward shoulder 21a is provided to prevent the spring 19 from driving the contact 17 out of the bore 16. An electrical connector 22 is provided, leading to one side of the source of energy for the flash-bulb. The flash-bulb 23 is attached to the socket 3 by passing the bulb-base 24 into the bore 16, the conventional bayonet prongs 25 (which are not utilized in retaining the bulb within the socket 3) being caused to enter longitudinal slots 26 in the socket. As the bulb-base 24 is pushed into the bore 16, the centrally disposed contact 21 on the bulb base will be forced into engagement with the central contact 17, and as it is usual that the contact 21 is formed of a relatively soft, solder-like metal, the abrading point 18 of the contact 17 will be forced into the contact 21 where fresh metal will be engaged, forming a very satisfactory contact. The insertion of the bulb base also causes the smooth sidewall portion of the base 24 which extends parallel to the direction of movement of the bulb, to be engaged by the abrading point 28 on the free-end of the finger 10, which will scrape along such side-wall portion and abrade the surface thereof. This serves to remove any accumulated oil, grease, dirt or other relatively high electrical resistance contaminant, and this abrading point 28 may actually be caused to scrape down into the metal of the base 24, providing a very low resistance contact. The return circuit for the battery or other source of energy may be conducted through the finger 10, the portions 6, 7 and 9 of the bulb-retaining means to the battery case 8, where it may connect to the opposite side of the battery from that to which the conductor 22 is connected.

When the bulb 23 has been pushed in as far as it is desired, the bias built up in the spring 19 by the rearward movement of the contact 17 will serve to crowd the bulb-base 24 outwardly against the holding action of the spring finger 10, causing the same to more firmly abrade the side-wall portion. When it is desired to release a spent bulb from the socket, it is merely necessary to depress the release lever 12 to the dot-dash po-

sition 12b, pulling the free end 10a of the finger 10 away from the side-wall of the bulb-base, whereupon the spring 19 will eject the bulb from the socket bore 16.

Referring to Figs. 3 and 4 of the drawings, I have illustrated a modification of the structure shown in Figs. 1 and 2, wherein the retaining finger which is adapted to engage the side wall portion of the bulb base is formed as a separate element, pivotally mounted with respect to the socket member. This form of the device may comprise a support 31, to which a socket 32 and a reflector 33 are attached through the agency of a snap ring 34. The bulb-retaining and abrading means may comprise a base member 35 carrying a retaining finger 36 having an abrading contact point portion 37 operating through a slot 38 in the side-wall of the socket 32 and adapted for pivotal movement through a minor angle with respect to the base 35 as through a pivot pin mounting 39 which may be defined by up-standing ears 40 and depending ears 41 on the base 35 and the finger 36, respectively. A spring member 42 may be coiled about the pivot pin 39, with portions extending into biasing engagement with the members 35 and 36, to exert a rotative effort upon the finger 36 in a counter-clockwise direction as viewed in Fig. 3, and cause the contact point 37 to resiliently engage the side wall of the base 43 of a bulb 44. This spring 42 is shown in dotted lines in Fig. 4; omitted in Fig. 3. As the bulb is inserted within the socket 32, the point 37 will be engaged, and the finger 36 rotated clock-wise as to the position shown in full lines in Fig. 3, and the desired release of the abrading point 37 may be obtained by depressing the extension 45 of the finger 36 outwardly of the pivot 39, moving the finger 36 as to the dot-dash position shown in Fig. 3.

The socket 32 is provided with a spring contact construction comparable to that shown at 17-21 in Fig. 1, as at 46. The socket 32 may be of metal, if desired, in which case the rear wall thereof is preferably formed of insulating material, and may comprise a washer 47 inserted within a recess at the rearward end of the socket and maintained therein by spinning the end portions of the socket over the washer as at 48. The retaining finger 36, the base member 35 and support 31 may be formed of electrically conductive material such as metal, whereby the desired supply of electric energy to the bulb 44 may be established through lead 49 and the contact 46 for one side and through the support 31 base member 35 and finger 36 to the other side.

In Figs. 5-7 I have shown a form of this invention which is incorporated in the body or casing portion of a camera, for example, and referring thereto a camera body portion is indicated at 51 provided with a tubular portion 52 defining a socket adapted to receive the base portion 53 of a bulb 54. The tubular portion 52 is recessed at opposite sides, as at 55, to receive the customary bayonet prongs with which the bulb 54 is usually provided, and at a position removed from the location of the grooves 55 I provide a slot 56 within which the bulb retaining means may function. In this form of device the bulb retaining means may comprise a lever member 57 having a contact portion 57a disposed within the slot 56 and terminating in an abrading point 58 which is adapted to engage the side wall of the bulb base 53 in a manner corresponding to engagement provided at 28 and 37 in the first described forms of the device. The lever member 57 is

mounted to establish a swinging movement of the portion 57a within the slot 56 as between the full-line and dot-dash positions illustrated in Fig. 5, and to this end I may provide the lever member 57 with a straight central portion 57b which is pivotally attached to the camera casing 51 within a suitable elongated channel or groove 59, and retained therein by staking or the like as at 60, together with an actuating portion 57c depending within the casing 51 and adapted to be engaged by an operating member 62. The operating member may comprise a shoulder member 63 mounted on a push rod 64 carrying a push button 65 extending through the side wall of the casing in position for manual engagement, said rod member and the shoulder 63 being biased outwardly through the agency of a spring member 66. The shoulder member 63 is thus biased to the left, in Fig. 5, causing a clockwise rotation of the lever 57, carrying the portion 57a to the full line position illustrated. The desired retraction or movement of the portion 57a out of contact with the bulb base may be effected through the agency of a second shoulder member 67 preferably spaced from the shoulder 63 sufficiently to receive the depending lever portion 57c. The portion of the shoulder 67 facing the lever portion 57c is preferably tapered as at 67a to facilitate the smooth rotative operation of the lever 57 when the button 65 is pressed inwardly.

The operation of this form of device will be apparent from the drawings and the above description, it being comprehended that a spring contact assembly 68 comparable to structures 17-21 and 46, above, will be provided to secure the desired abrading contact of a central terminal of the bulb and the desired ejection of the bulb from the socket upon release of the lever 57, the desire electrical supply being provided through lead 69 and the casing 51.

In the forms of device shown in Figures 1 through 7, the free end portion of the bulb retaining means which functions to secure the desired abrading contact of the bulb base side wall, is inclined forwardly in the direction of insertion of the bulb-base within the socket so that a "toggle" action is obtained upon the bulb retaining means under the biasing influence of the spring contact which engages the central terminal of the bulb, this action causing the biasing effort exerted by the central spring contact to result in a more firm abrading engagement with the bulb side wall; the greater the biasing effort exerted by the spring upon the central contact, tending to eject the bulb from the socket, the greater the resulting retaining action of the bulb retaining means, and the more intimate the abrading electrical engagement of the retaining means with the electrical contact defined by such side wall of the bulb-base.

The lateral thrust against the bulb-base side wall effected by the abrading retaining fingers 10, 36 and 57a will push the bulb-base toward the opposing side wall of the socket bore, and where such socket is of an electrically conductive nature, as in Figs. 3-7, this will contribute to the desired low electrical resistance.

Fig. 8 I have illustrated an abrading contact structure adapted to provide abrading engagement with the central contact and side wall portions of a bulb-base, where reliance is placed on other means for retaining the bulb in place with the socket, thus attaining the electrical advantages of this invention. Referring to this figure, a socket construction is illustrated at 71,

7 provided with a central abrading contact 72 provided with a biasing spring 73 and adapted to engage the central terminal 74 of a bulb-base 75, such bulb-base being retained within the socket 71 through the agency of the conventional bayonet prongs 76 in cooperating with a bayonet slot construction 77 of conventional form in the socket itself. The electrical contact to the side wall of the base 75 is provided through a resilient spring contact member 78 secured to a fixed portion of the socket assembly such as a support 79 and carrying an abrading point 80 at its free end portion, which point 80 may be extended through a suitable opening 81 in the side wall of the socket 71. Upon insertion of the bulb within a socket 71 the base 75 is mechanically and electrically engaged by the abrading point 80, which scratches into the base metal through any accumulated interfering film at the side wall portion of the base, while the point 82 of the central spring contact assembly will penetrate and electrically engage with the terminal 74.

Numerous modifications in the structure of this invention will occur to those skilled in the art, the delineated forms of the invention being illustrative only, and I choose therefore not to be limited to the specific details herein set forth but rather to the scope of the subjoined claim.

It will be understood that the abrading contact portions 28, 37, 58 and 80 in the above described embodiments of my invention are each provided with a sharp edge or point (as illustrated most clearly in Figs. 1 and 5) positioned for engagement with the contact area at the smooth side wall portion of the bulb base so as to not only scratch through any accumulated interfering film on such contact area but into the metal itself, thus cutting into or scarifying the metallic surface, whereby they attain mechanical engagement with the bulb base as well as providing low resistance electrical contact.

Furthermore, it will be appreciated that the abrading contact means employed at the central contact zone, for example, or the abrading contact means shown at 19a, 37, 58 or 80 are not necessarily mounted directly upon the guide means adapted to receive the bulb-base or other connection element; however, for the purpose of simplification of wording, the broad terminology of the subjoined claim refers to such contact means as being mounted upon the guide means, and it is my intention that this expression be interpreted as including structures in which the contact means may be supported in some generally fixed relation to the guide means, as being mounted upon an ancillary structural element which is relatively fixed with respect to the guide means. As in Fig. 8, for example, the contact member 80 is mounted upon the support 79, which

5 may be integral with or merely attached to the socket 71.

I claim:

An electrical socket construction adapted for the reception and retention of an electrical element provided with two spaced contact areas at which electrical connections are to be established upon relative movement of said socket and said element with respect to one another, one of said contact areas being disposed at the inner end of said element and the other of said contact areas having a smooth surface extending parallel to the direction of such relative movement, which comprises: means defining a guide member for reception of said element; electric contact means at the inner end of said guide member in position to engage said one contact area of said element upon reception of said element within said guide member and provided with an abrading member adapted to effect an abrasion of said one contact area during such engagement, said contact means being provided with spring means biasing the same outwardly of the socket toward one position and being movable inwardly away from said one position against such bias by engagement with said one contact area upon insertion of said element within said guide member to thereby cause such bias to be imposed upon said element in such opposite direction; and an electrically conductive toggle member mounted in fixed relation with respect to said guide member at one side thereof and having an abrading end portion resiliently biased toward the position of and adapted to engage said other contact area and abrade the same upon insertion of said element, said toggle member being movable at said end portion for displacement under such engagement to a position such as to be inclined forwardly in the direction of relative movement of said element during such insertion and thereby position said element against ejection from said socket under the biasing action of said spring.

GORDON B. POLLOCK.
